Primary Examiner — Ricky Pham(74) *Attorney, Agent, or Firm* — Hubbard Johnston, PLLC**CLAIM**

The ornamental design for a spoon, as shown and described.

DESCRIPTION

FIG. 1 is a top view of a spoon showing my new design;

FIG. 2 is bottom view thereof;

FIG. 3 is an enlarged front view thereof;

FIG. 4 is a right side view thereof;

FIG. 5 is a left side view thereof;

FIG. 6 is an enlarged perspective view thereof; and,

FIG. 7 is an enlarged rear view thereof.

The broken lines illustrate structure or features that form no part of the claimed design.
